UNITED STATES PATENT OFFICE

2,011,242

ASH TRAY

Joseph W. Girard, Los Angeles, Calif.

Application February 25, 1932, Serial No. 595,161
Renewed April 2, 1934

3 Claims. (Cl. 131—51)

This invention relates to ash trays and the general object of the invention is to so construct the ash tray that there is no possibility of the cigar or cigarette disposed on the tray falling on the floor or table or anywhere except into the tray itself.

A further object is to provide a construction of this character in which the support for the cigar or cigarette is so constructed that a two edge contact with the cigar or cigarette is provided.

Another object is to provide the tray with supporting rests, as they may be called, detachably mounted upon the body of the tray, these supporting rests with the parallel walls of the tray constituting means for supporting the cigar or cigarette and being detachable from the body of the tray so that the tray may be readily emptied.

Other objects will appear in the course of the following description.

20 My invention is illustrated in the accompanying drawing, wherein:—

Figure 1 is a perspective view of an ash tray constructed in accordance with my invention;

Fig. 2 is a top plan view of the blank from which the rack or rest is made;

Figure 3 is a fragmentary cross section through the ash tray to illustrate the manner in which a cigarette will fall when it is burned beyond a certain point.

30 Referring to the drawing, 10 designates the body of the tray which may be of any suitable construction or material. This tray has its opposite walls formed along their upper edges with convolutions forming a series of depressions or valleys 11 separated by raised portions. The other two walls of the tray are formed preferably with depressions 12. The tray, of course, has the usual bottom 13. This tray may be made of metal, glass or any other suitable material.

40 Coacting with the body of the tray are supporting members designated 14 arranged in parallel relation and preferably connected by the transverse cross bars 15. As illustrated, these cross bars and the members 14 are stamped from one piece of metal, the members 14 being bent up at right angles to the bars 15. The members 14 at their extremities are formed with the hooked portions 16 and these members 14 are so spaced from each other as to engage within the recesses 12 50 with the hooks engaging over the side walls of the body of the tray.

The portions 14 which constitute rests upon which the cigarette or cigar may be laid are also convoluted upon their upper edges to provide the depressions 17 to correspond with the de-

pressions 11 in the parallel walls of the tray. This rest, composed of the members 14 and the cross bars 15, may be constructed of metal, glass or any other suitable material. These members 14 might be made in one piece with the body of the tray, though preferably they are separate pieces so that they may be removed from the body of the tray to permit the body of the tray to be emptied.

The distance between the members 14 is less than the length of an ordinary cigarette and the distance between either of the members 14 and the adjacent wall 11 is less than that of an ordinary cigarette. It will be seen that no matter how a cigar or cigarette is placed upon the rests 14 and upon the walls 11, the burning cigarette, if it continues to burn until the lighted end of the cigarette burns beyond the rest 14, will fall within the tray, as illustrated in Figure 3, thus preventing all damage by fire from a smoldering cigarette falling upon a table or upon the carpet or floor. Whether the cigarette be placed upon the rests 14 or upon one end wall 11 and upon the rest 14, the cigarette or cigar when it burns down sufficiently will fall into the tray. By supporting the cigar or cigarette upon the rests 14 or upon one of the rests and the end wall of the tray, the tobacco in the cigars or cigarettes is prevented from gathering moisture or "sweat" on the lighted end.

35 That end of a cigar or cigarette which is inserted in the mouth will be held from coming in contact with the metal holder unless the cigar or cigarette burns up sufficiently to allow the article to fall into the tray.

It will be seen that the distances between the rests 14 and the parallel walls of the tray are such as to compel a smoker to place a cigar or cigarette on the tray in such a manner that the longer end of the cigar or cigarette is inside of 40 the tray. A pipe may also be held in an upright position between one end of the tray and one of the rests 14. This will hold the pipe in an upright position, preventing fire and ashes from falling from the bowl of the pipe.

45 I claim:—

1. An ash tray comprising a body having four upstanding walls, two of the opposite walls being recessed upon their upper edges, and a pair of rests connected by cross bars, the rests being of relatively thin material and disposed in vertical planes parallel to opposed walls, the extremities of the rests fitting within the recesses in the first named walls, and the walls extending par- 50 55

- allel to the rests being formed with alternate elevations and depressions.
2. An ash tray comprising a body having four upstanding walls, opposite walls being formed with depressions in their upper edges, and a pair of rests formed of thin sheet metal connected by integral cross bars, the rests extending in vertical planes and having their upper edges formed with alternate elevations and depressions, the extremities of the rests being formed with hooks to hook over the side walls within said depressions, and the end walls of the tray having their upper edges formed with alternate elevations and depressions.
5. As an article of manufacture, a blank for forming a rest for cigarettes or cigars comprising a metallic sheet, the center of said sheet being provided with a rectangular cut-out whereby the blank has the form of a frame comprising longitudinally extending parallel members and integral cross members connecting the parallel members, the longitudinal members extending at right angles to the connecting members and parallel to each other, and the outer edges of the 10 longitudinal members being sinuous. 5

JOSEPH W. GIRARD.
